(57) **CLAIM**

The ornamental design for a radio frequency radiation shield unit for wireless telephones, as shown and described.

DESCRIPTION

FIG. 1 is a front perspective view of the radio frequency radiation shield unit for wireless telephones;

FIG. 2 is a top plan view thereof;

FIG. 3 is a right side elevation view thereof;

FIG. 4 is a rear elevation view thereof;

FIG. 5 is a bottom plan view thereof;

FIG. 6 is a left side elevation view thereof; and,

FIG. 7 is a front elevation thereof with a cellular telephone shown in phantom lines.

The phantom line showings of FIG. 7 are for illustrative purposes only and form no part of the claimed design.
